GARDNER CHILSON, OF BOSTON, MASSACHUSETTS.

Letters Patent No. 79,312, dated June 30, 1868.

IMPROVEMENT IN STOVE-GRATES.

The Schedule referred to in these Letters Patent and making part of the same.

TO ALL PERSONS TO WHOM THESE PRESENTS MAY COME:

Be it known that I, GARDNER CHILSON, of Boston, in the county of Suffolk, and State of Massachusetts, have invented a new and useful Improvement in Grates for Stoves; and I do hereby declare the same to be fully described in the following specification, and represented in the accompanying drawings, of which—

Figure 1 is a top view,

Figure 2 a side elevation,

Figure 3 an end view,

Figure 4 a longitudinal section, and

Figure 5 a transverse section of my improved grate.

The said grate is rectangular in its general form, and composed of a frame, *a*, and a series of cross-bars, *b b b*, &c., the latter having open spaces *c c c*, &c., between them, and being parallel to each other and to the ends of the frame.

This grate is arched both longitudinally and transversely, in manner as represented in the drawings. Each side bar, besides being crowned on its top surface, is deeper at its middle than it is at its ends, the same imparting to it the truss-form, as shown in the drawings.

Furthermore, there are journals *d d* projecting from the middles of the end bars of the frame; and there is also a bent arm, *e*, having an elbow on it, as shown at *f*, extended downward from one of the side bars of the frame, and between one of the journals and one of the side bars of the frame. This arm has a hole, *g*, made through its lower part to receive the hook *h* of a hooked rod or bar, having the form as shown in side view in fig. 6. This rod or bar is intended to go through a hole in one of the front plates of the fireplace in which the grate is to be used. The rod or bar has a notch, *i*, to catch on the edge of the hole, such being for the purpose of holding the grate horizontal when it may be in use.

By raising the notch out of connection with the plate, the grate may be shaken by the rod, or turned so as to discharge coals into the ash-pit or chamber that may be below it.

The elbow on the arm is to carry the arm out of the way of the drawer or ash-pan usually introduced into the ash-chamber.

I am aware that a circular grate provided with journals has had an arm extended down from its centre, such arm being to receive a rod, and to aid in enabling a person either to turn or shake the grate, as occasion may require. I therefore make no claim to such. When at the centre, the arm is liable to get more or less buried in the ashes of the ash-chamber, or to be clogged thereby, but when arranged at the end of the grate, and particularly when provided with a bend or elbow to cause it to extend horizontally beyond such end, and the end of the ash-drawer, it will be out of the way of the ashes which may fall through the grate, and cannot be interfered with by such. When the arm extends down from the centre of the grate, such arm is in the way of an ash-drawer, or prevents such from being used in the ash-chamber, as in such case the drawer cannot be moved into and out of place, as the arm will be an obstruction thereto. Furthermore, by arranging the arm eccentrically with respect to the axis of the grate, in the manner represented, I am enabled to increase the leverage exerted by it on the grate beyond what it would be were the arm to extend down from the axis of the grate.

The peculiar arching of the grate, and the truss-form of its side bars, renders it very strong, and not liable to sag in the middle when over-heated or heated to redness.

I claim the square or rectangular grate as arched or curved both longitudinally and laterally, and having its side bars trussed or made deeper at their middles than at their ends, as represented.

I also claim the combination and arrangement of the elbow of the grate-arm, with such arm and the grate, constructed and disposed relatively to each other substantially as specified.

GARDNER CHILSON.
